His Attorney.

UNITED STATES PATENT OFFICE

2,324,327

DYNAMOELECTRIC MACHINE BRUSH
RIGGING

Paul B. Shaffer, Fort Wayne, Ind., assignor to
General Electric Company, a corporation of
New York

Application October 23, 1942, Serial No. 463,089

11 Claims. (Cl. 171—323)

My invention relates to brush riggings and more particularly to a brush rigging adapted to be used with a dynamo-electric machine which rotates bodily.

An object of my invention is to provide an improved brush rigging.

Another object of my invention is to provide an improved brush rigging for a bodily rotatable dynamo-electric machine wherein centrifugal force has substantially no effect on the pressure of the brush on an electrical contact member of the machine.

Further objects and advantages of my invention will become apparent and my invention will be better understood from the following description referring to the accompanying drawing, and the features of novelty which characterize my invention will be pointed out with particularity in the claims annexed to and forming part of this specification.

In the drawing, Fig. 1 is a side elevational view of a brush rigging provided with an embodiment of my invention with a substantially unused electrical contact brush therein; Fig. 2 is a side elevational view of the arrangement shown in Fig. 1, partly broken away, illustrating a substantially worn-out contact brush; Fig. 3 is an end view, partly broken away, of the construction shown in Figs. 1 and 2 taken along line 3—3 of Fig. 1; Fig. 4 is an outline illustration of the brush holder shown in Figs. 1 to 3 illustrating the forces acting thereon due to the machine rotating bodily about its axis; and Fig. 5 is a side elevational view of the brush rigging shown in Fig. 1.

Referring to the drawing, I have shown a brush rigging adapted to be used with a bodily rotatable dynamo-electric machine having an electrical contact commutator member 10 to which the windings of the rotatable member of the machine may be connected. This type machine requires a special type brush rigging to prevent sticking of the brushes in brush holders or of brush holders on their supports due to centrifugal force and to prevent centrifugal force from biasing the electrical contact brush out of contact with the current collector element. In my improved construction, centrifugal force due to the machine rotating bodily about its axis has substantially no effect on the biasing of the electrical contact brush relative to the current collector 10. This result is obtained by pivotally supporting an electrical contact brush 11 about an axis substantially at right angles to the action of centrifugal force, that is, about a pivotal support, the axis of which is substantially parallel to the action

of centrifugal force on the brush holder. My improved brush rigging includes a brush holder having two arms 12 and 13 extending from a hub 14. The arm 12 is formed at the outer end thereof as a brush support 15 in which the brush 11 is arranged and to which the brush is secured by a screw 16. The brush holder arm 13 is formed at its outer end with a balance weight 17 such that the arm 12, together with its brush 11 and securing screw 16, has substantially the same weight as the arm 13 and its balance weight 17. Furthermore, the masses of the two arms and associated elements are such that the center of gravity 18 of the arm 12 and its associated equipment is located at a distance *a* from the center of gravity 19 of the entire brush holder substantially equal to the distance *b* of the center of gravity 20 of the arm 13 and its weight 17 from the center of gravity of the brush holder. The brush holder hub 14 is rotatably supported about a pivot pin 21 having an axis substantially at right angles to the axis of rotation of the dynamo-electric machine, and this pivot pin is arranged to provide a pivotal support for the brush holder arms substantially through the center of gravity 19 of the brush holder, providing substantially equal moments for each of the arms 12 and 13 about a point on the axis of the pivot pin 14 due to centrifugal forces F_a acting on the arm 12 and F_b on the arm 13 when the machine rotates bodily. As shown in Fig. 4, the center of gravity of the brush holder will shift slightly as the brush 11 becomes worn, and moves from 19₁ to 19₂ for its extreme positions. This, however, is a relatively small change and has substantially no effect on the operation of the device. These centrifugal forces F_a and F_b act substantially parallel to the axis of the pin and through moment arms *a* and *b* which are substantially equal. Since the forces F_a and F_b have moments in opposite directions about the axis of the pin 21, there is substantially no resultant moment tending to rotate the brush holder at right angles to the axis of the pin 21 due to centrifugal force. This produces substantially an axial force or thrust on the pin 21 which is the sum of the centrifugal forces acting on the brush holder. This thrust on the pin 21 is transmitted through a thrust collar 22 formed on the outer end of the pin to a plurality of antifriction ball bearings 23 arranged in engagement with a thrust plate 24 within a bearing housing 25. The thrust plate 24 is held in position in the bearing housing 25 by an end plate 26 secured to the housing 25 by a pair of screws 27. The bearing housing 25 is

formed in a supporting bracket 28 and provides a journal bearing surface 29 for rotatably supporting the thrust plate end 22 of the pivot supporting pin 21. The other end of the pivot pin 21 is supported in a journal bearing element 30, also formed on the supporting bracket 28. With this construction, the brush holder is free to pivot about the axis of the pin 21 substantially transversely of the axis of rotation of the machine and towards or away from the current collecting commutator 10. In order to provide the desired biasing pressure of the contact brush 11 into engagement with the commutator 10, a biasing coil spring 31 is arranged about the central portion of the pivot pin 21 with one end 32 thereof arranged in engagement with the supporting bracket 28 and the other end 33 thereof arranged in engagement with the contact brush carrying arm 12. This spring 31 acts in a direction at right angles to the action of centrifugal force on the brush holder and, therefore, is substantially unaffected by centrifugal force resulting from the rotation of the machine bodily about its axis. The bearing bracket 28 may be suitably supported on the end shield 34 of the machine by securing bolts 35. With this construction, substantially all of the thrust on the brush holder resulting from the action of centrifugal force from the rotation of the brush rigging with the rotation of the machine is transmitted to anti-friction bearings 23 along the axis of the pivotal support of the brush holder and has substantially no effect in the direction in which the contact brush 11 is biased towards the current collector 10.

While I have illustrated and described a particular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent of the United States is:

1. A brush rigging for an electrical contact member of a dynamo-electric machine including a brush holder having two arms extending substantially transversely of the axis of rotation of said machine, one of said arms being formed to hold an electrical contact brush element, a pivot pin having an axis substantially at right angles to the axis of rotation of said dynamo-electric machine arranged to provide a pivotal support for said brush holder arms with substantially equal moments for each of said arms about a point on the axis of said pin due to centrifugal force acting on said arms in a direction substantially parallel to said pin, and means including a supporting bracket for rotatably supporting said pivot pin.

2. A brush rigging for an electrical contact member of a bodily rotatable dynamo-electric machine including a brush holder having two arms extending substantially transversely of the axis of rotation of said machine, one of said arms being formed to hold an electrical contact brush element, and a pivot support having an axis substantially at right angles to the axis of rotation of said dynamo-electric machine and to said arms and being arranged to support said brush holder arms with substantially equal moments for each of said arms about a point substantially on the axis of said support due to centrifugal

force acting on said arms by the rotation of said machine.

3. A brush rigging for an electrical contact member of a dynamo-electric machine including a brush holder having two arms extending substantially transversely of the axis of rotation of said machine, one of said arms being formed to hold an electrical contact brush element, a pivot pin having an axis substantially at right angles to the axis of rotation of said dynamo-electric machine and to said arms and being arranged to provide a pivotal support for said brush holder arms with substantially equal moments for each of said arms about a point substantially on the axis of said pin due to centrifugal force acting on said arms in a direction substantially parallel to said pin, and means for supporting said pivot pin.

4. A brush rigging for an electrical contact member of a dynamo-electric machine including a brush holder having two arms, one of said arms being formed to hold an electrical contact brush element, the other of said arms being provided with a weight thereon, a pivot pin having an axis substantially at right angles to the axis of rotation of said dynamo-electric machine arranged to provide a pivotal support for said brush holder arms substantially through the center of gravity of said brush holder with substantially equal moments for each of said arms about a point substantially on the axis of said pin due to centrifugal force acting on said arms in a direction substantially parallel to said pin, means for supporting said pivot pin, and means for biasing said contact element carrying arm toward an electrical contact member of said dynamo-electric machine.

5. A brush rigging for an electrical contact member of a dynamo-electric machine including a brush holder having two arms, one of said arms being formed to hold an electrical contact brush element, a pivot pin having an axis substantially at right angles to the axis of rotation of said dynamo-electric machine arranged to provide a pivotal support for said brush holder arms with substantially equal moments for each of said arms about a point on the axis of said pin due to centrifugal force acting on said arms in a direction substantially parallel to said pin, a mounting for said brush holder including means for transmitting axial thrust due to centrifugal force from said brush holder to said mounting, means for rotatably supporting said pivot pin on said supporting bracket, and means for biasing said contact element carrying arm toward an electrical contact member of said dynamo-electric machine.

6. A brush rigging for an electrical contact member of a dynamo-electric machine including a brush holder having two arms, one of said arms being formed to hold an electrical contact brush element, the other of said arms being provided with a weight thereon, means for providing a pivotal support for said brush holder arms substantially through the center of gravity of said brush holder with substantially equal moments for each of said arms about a point on the axis of said support and substantially at right angles to the axis of rotation of said machine due to centrifugal force acting on said arms in a direction substantially parallel to the axis of said support, a mounting for said brush holder including means for transmitting axial thrust due to centrifugal force from said brush holder, to said mounting, and means for biasing said con-

tact element carrying arm toward an electrical contact member of said dynamo-electric machine.

7. A brush rigging for an electrical contact member of a dynamo-electric machine including a brush holder having two arms extending substantially transversely of the axis of rotation of said machine, one of said arms being formed to hold an electrical contact brush element, a pivot pin having an axis substantially at right angles to the axis of rotation of said dynamo-electric machine and to said arms and being arranged to provide a pivotal support for said brush holder arms with substantially equal moments for each of said arms about a point substantially on the axis of said pin due to centrifugal force acting on said arms in a direction substantially parallel to said pin, a mounting for said brush holder including a supporting bracket having a bearing housing and a plurality of anti-friction ball bearings in said bearing housing, and means on said pin for transmitting axial thrust due to centrifugal force from said brush holder to said pin and from said pin to said anti-friction bearing.

8. A brush rigging for an electrical contact member of a dynamo-electric machine including a brush holder having two arms extending substantially transversely of the axis of rotation of said machine, one of said arms being formed to hold an electrical contact brush element, a pivot pin having an axis substantially at right angles to the axis of rotation of said dynamo-electric machine arranged to provide a pivotal support for said brush holder arms with substantially equal moments for each of said arms about a point on the axis of said pin due to centrifugal force acting on said arms in a direction substantially parallel to said pin, a mounting for said brush holder including a supporting bracket having a bearing housing and a plurality of anti-friction ball bearings in said bearing housing, means on said pin for transmitting axial thrust due to centrifugal force from said brush holder to said pin and from said pin to said anti-friction bearing, and means for rotatably supporting said pivot pin on said supporting bracket.

9. A brush rigging for an electrical contact member of a dynamo-electric machine including a brush holder having two arms, one of said arms being formed to hold an electrical contact brush element, the other of said arms being provided with a weight thereon, a pivot pin having an axis substantially at right angles to the axis of rotation of said dynamo-electric machine arranged to provide a pivotal support for said brush holder arms substantially through the center of gravity of said brush holder with substantially equal moments for each of said arms about a point on the axis of said pin due to centrifugal force acting on said arms in a direction substantially parallel to said pin, a mounting for said brush holder including means for trans-

mitting axial thrust due to centrifugal force from said brush holder to said mounting, means for rotatably supporting said pivot pin on said mounting, and means for biasing said contact element carrying arm toward an electrical contact member of said dynamo-electric machine.

10. A brush rigging for an electrical contact member of a bodily rotatable dynamo-electric machine including a brush holder having two arms, one of said arms being formed to hold an electrical contact brush element, the other of said arms being provided with a weight thereon, a pivot pin having an axis substantially at right angles to the axis of rotation of said dynamo-electric machine arranged to provide a pivotal support for said brush holder arms with substantially equal moments for each of said arms about a point substantially on the axis of said pin due to centrifugal force acting on said arms in a direction substantially parallel to said pin, a mounting for said brush holder including a supporting bracket having a bearing housing and a plurality of anti-friction ball bearings in said bearing housing, means on said pin for transmitting axial thrust due to centrifugal force from said brush holder to said pin and from said pin to said anti-friction bearing, means for rotatably supporting said pivot pin on said supporting bracket, and means for biasing said contact element carrying arm toward an electrical contact member of said dynamo-electric machine.

11. A brush rigging for an electrical contact member of a dynamo-electric machine including a brush holder having two arms, one of said arms being formed to hold an electrical contact brush element, the other of said arms being provided with a weight thereon, a pivot pin having an axis substantially at right angles to the axis of rotation of said dynamo-electric machine arranged to provide a pivotal support for said brush holder arms substantially through the center of gravity of said brush holder with substantially equal moments for each of said arms about a point on the axis of said pin due to centrifugal force acting on said arms in a direction substantially parallel to said pin, a mounting for said brush holder including a supporting bracket having a bearing housing and a plurality of anti-friction ball bearings in said bearing housing, means including a thrust plate element on said pin for transmitting axial thrust due to centrifugal force from said brush holder to said pin and from said pin to said anti-friction bearing, means including a journal bearing for rotatably supporting said pivot pin on said supporting bracket, and means including a biasing coil spring arranged about said pivot pin in engagement with said bracket and with said brush holder for biasing said contact element carrying arm toward an electrical contact member of said dynamo-electric machine.

PAUL B. SHAFFER.
